UNITED STATES PATENT OFFICE.

ANDREW P. GAGATEK, OF CHICAGO, ILLINOIS, ASSIGNOR, BY DIRECT AND MESNE ASSIGNMENTS, OF ONE-FOURTH TO JOHN RACZNIAK, ONE-EIGHTH TO STANISLAUS J. MASIOR, ONE-FOURTH TO KAJETAN KANIA, AND ONE-EIGHTH TO ROMAN ANTONI KIERAS, ALL OF CHICAGO, ILLINOIS.

RAIL-JOINT.

1,070,127.

Specification of Letters Patent.

Patented Aug. 12, 1913.

Application filed July 11, 1912. Serial No. 708,795.

To all whom it may concern:

Be it known that I, ANDREW P. GAGATEK, a subject of the Emperor of Austria, and a resident of the city of Chicago, county of Cook, and State of Illinois, have invented 5 certain new and useful Improvements in Rail-Joints, of which the following is a specification.

My invention relates to improvements in 10 rail joints and has for its object the provision for a construction of this character which may be applied readily to the adjoining ends of rails and which will hold 15 said rails securely in position.

The invention consists of the combinations and arrangements of parts hereinafter described and claimed.

The invention will be best understood by reference to the accompanying drawings 20 constituting a part of this specification and in which,

Figure 1 is a perspective view of a rail joint embodying my invention, shown in 25 position of use, and Fig. 2 is a side elevation of the rail joint with a socket member employed therein removed.

The preferred form of construction as 30 illustrated in the drawings comprises a rail 1 having a tongue receiving socket in one end of the web thereof, adapted to receive a tongue 2 formed on the end of the web of an adjoining rail 3. The tongue receiving socket is provided with interlocking enlargements 4 and 5 formed on tongue 2. At 35 its outer end, the tongue receiving socket is flared as indicated at 6 and the corresponding portion of tongue 2 is formed to fit snugly within this flared portion, so 40 as to reinforce the connection between the tongue 2 and the web portion of rail 3. A chair member is designed to fit over the joint thus formed between the two rails, said chair member comprising a base plate 45 7 having integral upstanding flanges 8 shaped to embrace and fit over the base portions and web of the adjoining ends of rails 1 and 3. These flanges 8 are connected with

base plate 7 by means of bracing webs 9 which are formed integrally with said 50 flanges and base portions. The base portion 7 is also perforated for the reception of suitable spikes or bolts 10 for securing said base portion to the ordinary railway ties 11, as indicated. In use, the chair 55 member is first slipped over the end of one of the rails to be joined, far enough to expose the tongue or the socket therein, and then the tongue and socket are engaged with each other. After this has been accomplished, the chair member may be readily 60 slipped over the joint thus formed as indicated in Fig. 1, and secured in position on the railway ties by means of spikes or bolts 10. With the chair member in position, it 65 will be observed, that it is impossible to disengage the ends of the rails, since tongue 2 can be removed from its socket only by lateral movement between the ends of the rails, and such movement is prevented by 70 the chair member. The specific form of construction illustrated will be found to be of durable construction and highly efficient in use.

While I have illustrated and described the 75 preferred construction for carrying my invention into effect, the same is capable of variation or modification without departing from the spirit of the invention. I, therefore, do not wish to be limited to the exact 80 details of construction set forth, but desire to avail myself of such variations and modifications as come within the scope of the appended claim.

Having described my invention, what I 85 claim as new and desire to secure by Letters Patent, is:

A rail joint comprising a rail having a socket in one end of the web thereof, said socket being downwardly and upwardly enlarged at its outer end, having circular recesses in its sides adjacent the enlargements thereof, circular recesses in its upper and lower sides at its inner end, said lower and upper sides having horizontally disposed 90 walls between said circular recesses, a rail

having a tongue projecting from the web thereof, extended into and shaped to snugly fit said socket; and a chair incasing the end portions of the webs and flanges of said rails forming a rigid connection between said rails, substantially as described.

In testimony whereof I have signed my

name to this specification in the presence of two subscribing witnesses.

ANDREW P. GAGATEK.

Witnesses:
